WALTER O. LUM, OF WILKINSBURG, PENNSYLVANIA, ASSIGNOR TO WESTINGHOUSE ELECTRIC AND MANUFACTURING COMPANY, A CORPORATION OF PENNSYLVANIA.

MOTOR-CONTROL SYSTEM.

1,196,124.

Specification of Letters Patent. Patented Aug. 29, 1916.

Application filed October 3, 1913. Serial No. 793,260.

To all whom it may concern:

Be it known that I, WALTER O. LUM, a citizen of the United States, and a resident of Wilkinsburg, in the county of Allegheny and State of Pennsylvania, have invented a new and useful Improvement in Motor-Control Systems, of which the following is a specification.

My invention relates to motor-control systems, and it has special reference to systems of control in which starting resistors are controlled by sets of automatically operated switches.

My invention has for one of its objects to provide a system of control which will be entirely automatic in its action and which will operate to cut out steps of the starting resistor in a predetermined order.

A further object of my invention is to provide a system of field control in which a single current-limit device may be employed both for retarding and for accelerating a motor.

In the operation of motors for driving planers, elevators and similar machinery requiring frequent stops and reversals, it is desirable that a system of control be employed that permits of rapid acceleration in starting and provides means for bringing the motor to a stop quickly and safely. It is essential to provide a system which is entirely automatic in its operation in order that the loss of time and the attention required in manually operated systems may be avoided.

My invention consists of a plurality of successively actuated switches which control the sections of the starting resistor of a motor circuit. Each of the actuating coils of the several switches is connected in the controlled circuit by the operation of the preceding switch. The last switch in the series comprises a series holding coil which operates to maintain the closure of this switch and thereby the short-circuiting of the entire resistor.

A field resistor is controlled both for acceleration in starting and for retardation in stopping the motor by the same current-limit switch. Means are provided whereby the functions of the current-limit switch are reversed when the motor is accelerated or retarded, respectively.

In the accompanying drawings, Figure 1 is a diagrammatic view of circuits and ap-

paratus embodying my invention. Fig. 2 is a view, similar to Fig. 1, of a modification.

Current is supplied from any suitable source, through line conductors 1 and 2, to a motor 3, the armature of which is indicated at 4. The motor is provided with a shunt field winding 5 which is controlled by a resistor 6. A sectional resistor 7, which is adapted to be connected in series with the armature 4, is controlled by a series of successively actuated electromagnetic switches 8, 9, 10 and 11 which comprise actuating coils 12, 13, 14, 15, respectively. The coil 12 acts also as a holding coil for the switch 8, while switches 9, 10, 11 are provided with holding coils 16, 17, 18.

A short circuit for the resistor 6 is controlled by a current-limit switch 19 and a reverse-current relay switch 20 which are connected in parallel circuits. The switch 19 is controlled by a coil 21 that is in series with the armature 4. The switch 20 is controlled by a coil 22, also in series with the armature 4, and by a shunt coil 23 which is wound to oppose the series coil 22. The parallel circuits of the switches 19 and 20 are controlled by a manually operated switch 24.

To start the motor, the switch 24 is moved to its upper position and a main switch 25 is closed. Current flows through a circuit which extends from the line conductor 2 through the switch 25, coil 12, resistor 7, armature 4, coils 21 and 22, conductor 26, and switch 25 to the line conductor 1. Current also flows through the shunt field winding 5 and the resistor 6 to the conductor 26. The coil 12 will be energized to close the switch 8 and thereby complete a short circuit through the coil 13 for one section of the resistor 7. The coil 12 acts as a holding coil for the switch 8 until the coil 13 has closed the switch 9 and thereby short circuited the coil 12 and the switch 8, allowing the latter to open. The closing of the switch 9 establishes a short circuit for a second section of the resistor 7 through the holding coil 16 and the actuating coil 14. The switches 10 and 11 are then closed in order, and a short circuit for the entire resistor 7 is established through the holding coil 18, thus insuring that the switch 11 will remain closed until the motor circuit is broken.

When the motor is being accelerated, the switch 20 is in its closed position, because current flows through the oppositely wound coils 22 and 23 in the same direction. In this position of the switch 20, a short circuit is established for a pair of contacts 27 controlled by the switch 19. As long as the armature current does not rise above a predetermined value, the switch 19 remains in its lower position and the resistor 6 is in series with the shunt field winding 5. When the armature current exceeds the value for which the switch 19 is adjusted, the coil 21 draws the switch upwardly to bridge a pair of contact members 28 and thereby short circuit the resistor 6 through the contact members 29 of the switch 24. The result is to strengthen the field of the motor and thus increase the counter electromotive of the motor. When the current falls to a normal value, the switch 19 again opens the short circuit to weaken the field of the motor and thus further accelerate the motor. The oscillations of the switch 19 will continue as long as the armature current fluctuates above the predetermined value.

When it is desired to stop the motor, the main switch 25 is opened and the switch 24 is thrown to its lower position. A dynamic braking circuit will then be established from the motor armature 4 through the coils 21, 22 and 23 back to the armature. Current generated by the motor armature now flows in reverse directions through the coils 22 and 23, and the switch 20 is opened to break the short circuit for contact members 27 of the switch 19. Current also flows through a shunt circuit comprising the shunt field winding 5, contact members 30 of the switch 24, contact members 27 of the switch 19 and conductors 31 and 32. When the switch 24 is thrown to its lower position, the circuit comprising the contact members 28 of the switch 19 is broken, and a short circuit for the resistor 6 is controlled by the switch 19 and the contact members 27.

When the current in the dynamic braking circuit exceeds the predetermined value at which the switch 19 operates, the latter breaks the short circuit for the resistor 6 which includes the contact members 27. The resistor 6 is inserted in series with the field winding 5 to weaken the motor field and thereby decrease the armature current. When the current falls below the predetermined value, the switch 19 falls to close the short circuit again and thereby strengthen the field of the motor to produce the maximum braking current. This operation of the switch continues until the current has fallen permanently below the predetermined value or until the motor has been brought to a stop.

By means of this arrangement, I am en-

abled to accelerate and retard motors within the shortest time possible consistent with safety. The current-limit switch insures that the current values will never become excessive but that, on the other hand, a maximum safe current will be employed both for acceleration and retardation of the motor armature.

A modification is shown in Fig. 2 in which like numerals designate corresponding parts. The switch 24 is so arranged as to be operated automatically instead of manually as in the system of Fig. 1. The switch 24 is provided with a coil 33 which is connected across the motor terminals. The switch 20 is provided with a pair of contact members 34 which are connected to the respective terminals of the coil 33. When the main switch 25 is closed and the switch 19 is in its lower position, the shunt coil 33 is energized to hold the switch 24 in its upper position. The several switches are then in their proper respective positions for accelerating the motor. The operation of the system differs in no other material respect from that of the system shown in Fig. 1.

When the dynamic braking circuit is established, the reverse-current relay switch 20 is moved to its upper position, as above explained in connection with Fig. 1, and the coil 33 is short-circuited, allowing the switch 24 to drop into its lower position. The switches 20 and 24 then occupy their proper respective positions for dynamic braking which is accomplished in the same manner as above described.

I claim as my invention:

1. In a control system, the combination with a motor, and a field resistor therefor, of a current-limit device for controlling said resistor and means for reversing the effects produced by the operation of said current-limit device.

2. In a control system, the combination with a motor, and a field resistor therefor, of a current-limit switch for controlling said resistor, and means comprising a reverse-current relay switch for controlling the effect of said current-limit switch.

3. In a control system, the combination with a motor, and a field resistor therefor, of means for automatically controlling said field resistor comprising a switch and automatic means for controlling the effects produced by the operation of said switch.

4. In a control system, the combination with a motor, of electro-responsive means for controlling the field strength of said motor, said means comprising a plurality of switches automatically controlled by the current through the armature of said motor, and means for controlling the effects produced by the operation of one of said switches.

5. In a control system, the combination

- with a dynamo-electric machine and a field resistor therefor, of a current-limit switch for automatically short circuiting said resistor when said dynamo-electric machine operates as a motor and for automatically breaking the short circuit when said dynamo-electric machine operates as a generator.
6. In a control system, the combination with a motor, of a switch for controlling the field strength of said motor and means controlled by the direction of current through the armature of said motor for controlling the effects produced by the operation of said switch.
- 10 7. In a control system, the combination with a motor and a field resistor therefor, of a current-limit switch for controlling said resistor, and means for reversing the effect of said current-limit switch comprising a plurality of switches, one of which comprises a plurality of coils wound to assist each other when connected in series.
- 15 8. In a control system, the combination with a motor and a field resistor therefor, of a current-limit switch for controlling a shunt circuit for said resistor, a dynamic-braking circuit for said motor, and means for reversing the effect of said switch when said braking circuit is established.
- 20 9. In a control system, the combination with a motor and a field resistor therefor, of a double-throw switch for controlling said resistor, means for rendering the switch inoperative in one of its positions when the motor is being accelerated and inoperative in its other position when the motor is being retarded.
- 25 10. In a motor-control system, the combination with an electric motor having a shunt field magnet winding, and a resistor in circuit therewith, of a switch for controlling a shunt circuit for said resistor, and means comprising a double-throw relay switch for reversing the effects produced by the operation of said controlling switch.
- 30 11. In a motor-control system, the combination with an electric motor having a shunt field magnet winding and a resistor in circuit therewith, of a pair of circuits in shunt relation with said resistor, and a pair of double-throw switches for controlling said circuits, one of said switches determining, by its position, the function of the other switch.
- 35 12. In a motor-control system, the combination with an electric motor having a shunt field magnet winding and a resistor in circuit with said winding, of a current-limit switch for controlling a shunt circuit for said resistor, and means comprising a double-throw reverse-current relay switch for controlling the functions of said current-limit switch.
- 40 13. In a motor-control system, the combination with an electric motor having a field magnet winding, and a resistor in circuit with said winding, of a current-limit switch for controlling a shunt circuit for said resistor, and a double-throw relay switch which operates, according to its position, to cause the current-limit switch to respectively close and open said shunt circuit when said current-limit switch is in its normal position.
- 45 14. In a motor-control system, the combination with an electric motor having a field magnet winding, and a resistor in circuit with said winding, of a current-limit switch for controlling a shunt circuit for said resistor, and a double-throw relay switch which operates, according to its position, to cause the current-limit switch to respectively open or close the shunt circuit when said current-limit switch is in its open position.
- 50 85 In testimony whereof, I have hereunto subscribed my name this 26th day of Sept., 1913.
